UNITED STATES PATENT OFFICE.

RICHARD BUTLER, OF NEW YORK, N. Y.

DESIGN FOR A COMB.

SPECIFICATION forming part of Design No. 12,540, dated October 25, 1881.

Application filed August 31, 1881. Term of patent 7 years.

To all whom it may concern:

Be it known that I, RICHARD BUTLER, of the city, county, and State of New York, have invented a new and original Design for Combs, 5 of which the following is a specification, reference being had to the accompanying drawing, forming part thereof.

In the drawing my design is represented by a side view of a comb.

10 The essential feature of the design is the circular tablet or medallion *a* upon the sides of the back portion of the comb in the space formed by the curved back edge, *b*. The back edge, *b*, curves outward from the ends of the 15 comb to the mid-length, so as to widen the space at the center. This line may be a sin-

gle, double, or irregular curve. The medallion gives a finish and ornamentation to the comb, and is applied alike on both sides. The medallion is embossed to represent the head of a 20 man in profile, and is to be applied to toilet, back, and round combs.

Having thus described my invention, I claim as new and desire to secure by Design Patent—

25 The design for combs herein shown and described, which consists of the curved edge *b*, forming a raised portion on the back, and the medallion or tablet *a* on the same.

RICHARD BUTLER.
